UNITED STATES PATENT OFFICE.

EMMA KNAPP, OF DENVER, COLORADO, ASSIGNOR TO WILLIAM F. KNAPP, OF DENVER, COLORADO.

HASP LOCK.

1,403,253.

Specification of Letters Patent. Patented Jan. 10, 1922.

Application filed October 27, 1920. Serial No. 419,788.

To all whom it may concern:

Be it known that I, EMMA KNAPP, a citizen of the United States, residing at Denver, in the county of Denver and State of Colorado, have invented certain new and useful Improvements in Hasp Locks, of which the following is a specification.

This invention relates to hasp-locks and more particularly to hasp locks of the type in which a key-controlled locking means cooperates with the staple to secure the hasp in place thereon.

It is the primary object of the present invention to provide a hasp-lock of the character above referred to in which the lock is mounted upon a support occupying a permanent position relative to the staple, and has a determinate movement on said support to be brought in cooperative relation to the staple.

Other objects of the invention reside in providing in connection with the support above referred to, a slide-way for the linear movement of the lock toward and from the staple, in providing a carrier movable on the slide-way, upon which the lock is movably mounted, in providing a means for the detachable connection of the lock with the carrier, and in providing means cooperative with the carrier to automatically hold it in an adjusted position, and to lift the hasp when the lock is being separated from the staple.

Further objects of my invention reside in details of construction and novel arrangements of parts, all of which will fully appear in the course of the following description made with reference to the accompanying drawings in which like characters of reference designate corresponding parts throughout the several views, and in which—

Figure 1 represents a side elevation of the cooperating members of my improved hasp-lock in its open condition;

Figure 2, a similar view of the hasp lock with its members in the locked position;

Figure 3, a partially sectional plan view taken on the line 3—3, Figure 1;

Figure 4, an enlarged detail view of the means for fastening the lock upon its carrier, taken along the line 4—4, Figure 1;

Figure 5, a side elevation of a modified construction of the hasp lock with its members in the locked position;

Figure 6, a similar view partly in section showing the members of the hasp-lock in a partially separated position, and

Figure 7, a similar view showing the key-controlled lock in the position it occupies when the hasp is removed from the staple.

Referring first to Figures 1 to 4, of the drawings, the reference characters 2 and 3 designate adjoining parts of two related objects fastened together by the hasp-lock, as for example, a door and its casing, or a box and its lid.

My improved hasp-lock comprises a staple 4 mounted on a base plate 5 which by means of screws or bolts is fastened to one of the objects, a hasp 6 hinged at the end of a plate 7 which by similar means is connected to the other object, and a key-operated lock 8 movably mounted with relation to the staple to be brought in locked connection therewith after the hasp is placed in its locking position.

The lock 8 which may be of any suitable construction, comprises a housing containing the usual key-controlled mechanism for the projection and retraction of a bow or shackle 9 adapted to pass through the staple after the lock is brought to its operative position with relation thereto.

The lock is movably mounted on a support which for convenience in construction may be formed integrally with the base plate of the staple.

In the construction shown in Figures 1 to 3 of the drawings the support consists of a tongue 10 projecting from the base plate of the staple in substantially parallel relation thereto and adapted to slidably support a carrier 12 upon which the lock is mounted.

The carrier consists of a block having a slot for its sliding connection with the tongue which is bent upwardly at its free end to provide a stop 12 limiting the outward movement of the same.

A plate 13 spaced from the upper surface of the block has a plurality of openings 13a to receive correspondingly positioned headed studs 14 on the under side of one of the ar-

ticulated members of a hinge 15 to the other member of which the lock is rigidly connected. Spring catches 16 shown in broken lines in Figure 4 secure the hinge upon the 5 plate.

The lock carrier has at its outer end a spring catch 17 which by engagement with the bent up end portion of the tongue secures the carrier in the position it occupies 10 when the lock is separated from the staple, and it has at its opposite end a lip 18 which under the same condition is engaged by the end of an arm 19 which has a resilient connection with the base plate of the staple.

15 A projection 20 on the hinge 15 of the lock limits the pivotal movement of the latter by engagement with the carrier.

The arm 19 has a slot 19^a through which the staple passes and it is bifurcated at its 20 free end to straddle the tongue 10 of the lock support.

The arm is depressed by the carrier when the lock is connected with the staple and it provides a support for the hasp 6 which 25 when the lock is subsequently returned to its inoperative position at the end of the tongue, is thrown upwardly by the movement of the arm to facilitate its removal from the staple.

30 In the operation of my invention the hasp is as usual placed upon the staple after which the spring arm which by engagement with the lip 18 of the carrier secured the latter in its inoperative position at the end 35 of the slideway, is depressed to release the carrier.

After the carrier has been placed adjacent to the staple as shown in Figure 2, the hinge 40 lock is adjusted to embrace one of the legs thereof and the shackle of the lock is projected by the action of the key on the operating mechanism of the same.

The parts of the hasp lock are in this manner securely locked together and can be 45 unfastened only by retraction of the shackle of the lock through the medium of the proper key.

After the lock has been opened it is lifted 50 from engagement with the staple and the carrier is moved rearwardly along the tongue until it again occupies its extreme position thereon as shown in Figure 1.

During the rearward movement of the carrier the spring arm moves upwardly by 55 its inherent resilience and lifts the hasp to facilitate its removal from the staple and after the carrier has reached its position at the end of the slide-way the arm by engagement with the lip 18 at the forward end 60 thereof, cooperates with the spring-catch 17 to hold the carrier in its adjusted position as hereinbefore explained.

Having thus described my improved hasp lock in its preferred form, its advantages 65 will be readily understood. The lock being

placed permanently in operative relation to the staple cannot be lost or misplaced and it is at all times in a position for immediate application.

The detachable connection of the lock 70 with its sliding carrier permits of its being used for other purposes or removed for repairs and it will be apparent that when the fastening is open, stealing of the lock may be readily prevented by closing it upon the 75 staple after the hasp has been separated therefrom.

The sliding and pivotal movements of the lock allow of its adjustment to its operative 80 position by finger pressure and the provision of the spring arm facilitates the removal of the hasp from the staple and moreover secures the lock in its adjusted position when separated from the other members of the fastening.

85 The modified construction illustrated in Figures 5 to 7 of the drawings is particularly adapted for use on flexible straps, such as those employed in fastening mail sacks and the like, and it differs from the first-described construction mainly in that the slide-way upon which the lock has its movement is pivoted as well as the lock itself.

The principal object of this arrangement 90 is compactness of construction which when the hasp lock must necessarily occupy a limited space as on a mail sack, is an obvious essential.

95 The lock support in the modified construction consists of an arm 21 formed at an angle to the base plate of the staple and provided at its extremities with knuckles for the pivotal connection of the slideway and the lock.

100 The slideway consists of a plate 22 formed integrally with a short stem 23 by means of which it is pivotally connected with one of the knuckles of the arm.

105 The plate is loosely fitted in a longitudinal recess 24 at the bottom of the lock and its stem passes through a slot in the lower surface of the same to permit of a linear movement of the lock upon the plate.

110 The pivotal connection of the lock with the arm of the support is established 115 through the intermediary of a short link 25 connecting the other knuckle of the arm with a corresponding knuckle at the end of a bracket 26 extending downwardly from the end of the lock.

120 The device for lifting the hasp consists in this form of my invention of a lever 27 which is pivoted upon the pintle of the hinge connection of the slideway 22.

125 One of the arms of the lever is positioned to engage the underside of the hasp after it is placed upon the staple and its other arm is disposed to be engaged by the lock when it turns about its pivot to its inoperative position.

A spring-catch 28 on the lock cooperates with the knuckle at the lower end of the arm of the support to hold the lock in its adjusted position when separated from the

5 staple as shown in Figure 7, and the catch 28 is preferably positioned to engage the arm of the lever when the fastening is closed as illustrated in Figure 5.

The staple and the lock-support are con-

10 jointly mounted at an end portion of the flexible strap 29 to which the hasp-lock is applied, while the hasp is pivotally connected at the opposite end of the same by means of a link 30.

15 Inasmuch as the operation of the modified form of the hasp lock is similar to that of the first-described construction, no further explanation is deemed necessary.

Having thus described my invention what

20 I claim and desire to secure by Letters-Patent is:

1. A hasp-lock of the character described comprising in combination, a staple, a hasp cooperating therewith, a lock-support, and a 25 pivoted lock slidably mounted on the support.

2. A hasp-lock of the character described comprising in combination, a staple, a hasp cooperating therewith, a lock-support fixed 30 with relation to the staple, and a pivoted lock slidably mounted on the support.

3. A hasp-lock of the character described comprising in combination, a staple having a base-plate, a hasp cooperating with the 35 staple, a lock support formed on the base-plate, and a pivoted lock slidably mounted on the support.

4. A hasp-lock of the character described comprising in combination, a staple, a hasp 40 cooperating therewith, a lock-support fixed with relation to the staple, a lock movable on the support to be brought in an operative position with relation to the staple, and automatic means to secure the lock in a position 45 in which it is separated from the staple.

5. A hasp-lock of the character described comprising in combination, a staple, a hasp 50 cooperating therewith, a lock-support fixed with relation to the staple, a lock movable on the support to be brought in an operative position with relation to the staple, and hasp-lifting means operated by movement of the lock to a position in which it is separated from the staple.

55 6. A hasp-lock of the character described comprising in combination, a staple, a hasp 55 cooperating therewith, a lock-support fixed with relation to the staple, a lock movable on the support to be brought in an operative position with relation to the staple, and hasp-lifting means operated by movement of the lock to a position in which it is separated from the staple and adapted to secure the lock in its last-mentioned position.

65 7. A hasp-lock of the character de-

scribed comprising in combination, a staple, a hasp cooperating therewith, a lock-support, a carrier movable thereon, and a lock movable on the carrier.

8. A hasp-lock of the character described 70 comprising in combination, a staple, a hasp cooperating therewith, a lock-support, a carrier slidable thereon, and a lock movable on the carrier.

9. A hasp-lock of the character described 75 comprising in combination, a staple, a hasp cooperating therewith, a lock-support, a carrier movable thereon, and a lock pivoted on the carrier.

10. A hasp-lock of the character described 80 comprising in combination, a staple, a hasp cooperating therewith, a lock support, a carrier movable thereon, and a lock detachably mounted on the carrier.

11. A hasp-lock of the character described 85 comprising in combination, a staple, a hasp cooperating therewith, a lock-support, a carrier movable thereon, a hinge detachably mounted on the carrier, and a lock fastened 90 to the hinge.

12. A hasp-lock of the character described comprising in combination a staple, a hasp 95 cooperating therewith, a tongue projecting from the staple, a carrier slidable on the tongue, and a lock on the carrier.

13. A hasp-lock of the character described comprising in combination a staple, a hasp 100 cooperating therewith, a tongue projecting from the staple, a carrier slidable on the tongue, a lock on the carrier, and means to automatically lock the carrier in its position at the free end of the tongue.

14. A hasp-lock of the character described comprising in combination, a staple having a 105 base plate, a hasp cooperating with the staple, a tongue formed on the base plate of the staple, and a lock slidably mounted on said tongue.

15. A hasp lock of the character described comprising in combination, a staple having 110 a base-plate, a hasp cooperating with the staple, a lock support, a member having a resilient connection with the base plate and adapted to move upwardly against the hasp on the staple, and a lock movable on the support to a position cooperative with the staple, in restraining contact with said member.

16. A hasp-lock of the character described comprising in combination, a staple, a hasp 115 cooperating therewith, a lock support, a resilient arm adapted to move upwardly against the hasp on the staple, and a lock movable on the support to a position cooperative with the staple, in restraining contact with the arm.

17. A hasp lock of the character described comprising in combination, a staple, a hasp 120 cooperating therewith, a lock support, a resilient arm adapted to move upwardly against the hasp on the staple, and a lock 125 movable on the support to a position cooperative with the staple, in restraining contact with the arm.

movable on the support to a position cooperative with the staple, in restraining contact with the arm, the arm when released being capable of securing the lock in a position it occupies when separated from the staple.

18. A hasp-lock of the character described comprising in combination, a staple, a hasp cooperating therewith, a lock support, a lock movable thereon to a position cooperative with the staple, and a resilient member adapted to automatically secure the lock in

an adjusted position in which it is separated from the staple.

19. A hasp lock of the character described, comprising in combination a staple, a hasp cooperating therewith, a lock support fixed with relation to the staple, and a lock movable on the support to engage with the staple after the hasp is in place thereon.

20 In testimony whereof I have affixed my signature.

EMMA KNAPP.
